IMPACT WRENCH

Clifford E. Fitch, Bryan, Ohio, assignor to The Aro Equipment Corporation, Bryan, Ohio, a corporation of Ohio

Application February 27, 1945, Serial No. 579,913

6 Claims. (Cl. 192—30.5)

1

My present invention relates to an impact tool such as one for driving wrench heads and the like, the mechanism thereof being driven by a pneumatic motor or the like.

One object of the invention is to provide an impact clutch connection between a motor and a wrench or similar tool, such connection being comparatively simple in construction and involving a minimum number of parts which are inexpensive to manufacture.

Another object is to provide an impact clutch connection which utilizes centrifugal force to effect an operative connection while rotating a nut, bolt or the like, and upon a predetermined resistance to turning torque being offered by the nut or bolt, the mechanism automatically changes to an impact operation wherein the hammer elements alternately strike and release anvil elements to thereby secure a tightening of the bolt or nut to the desired degree.

Still another object is to provide a connection between a driving element and an anvil element consisting of rollers or similar hammer elements or impact members carried by the driving element and freely movable radially relative thereto, their outward and inward movements being limited, with the rollers in position when at their outer limits of movement to strike anvil-like projections or abutments of the anvil element and thereafter being released from the anvil-like projections by an inward camming action between the projections and the rollers.

A further object is to provide an impact clutch connection utilizing rollers as hammer elements which are freely rotatable to distribute the wear around them, and which are limited in their radial movements relative to a driving element so that they may stop rotation due to frictional engagement with the limiting means and strike the anvil-like projections while they are not rotating, thus eliminating a "climbing" effect of the rollers on the cam surfaces of the anvil-like projections.

Still a further object is to provide a modified form of structure which uses slidably mounted but non-rotatable hammer elements.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Fig. 1 is a side elevation of an impact tool embodying my invention, portions of the motor and the impact mechanism being shown in section;

2

Fig. 2 is a sectional view on the line 2—2 of Fig. 1, showing the cooperating parts of the impact mechanism in impacting position;

Fig. 3 is a similar sectional view wherein the hammer elements have been retracted due to further rotation of the driving element;

Fig. 4 is a perspective view of the driving element; and

Fig. 5 is a sectional view similar to Fig. 3 showing a modified construction.

On the accompanying drawing I have used the reference character M to indicate, in general, a motor such as one of the pneumatic type. The shaft of the motor is shown at 10 and constitutes the prime mover for the impact mechanism and a wrench head 12. The wrench head is mounted on a wrench shaft 16 having a squared portion 18 cooperating with the socket-like wrench head to rotate the head with the shaft.

20 The shaft 16 is journaled in a bearing portion 20 of a housing 14 and has, on its inner end, a disk 22. The disk 22 may be termed an anvil element and has a pair of anvil projections or abutments 26. The housing 14 is secured to the motor M and is adapted for housing the anvil element and the cooperating parts between it and the shaft 10, which will now be described.

25 A driving element or carrier member is shown at 28. This element is relatively heavy and serves somewhat as a fly wheel. It is driven by the motor shaft 10, as by being splined thereto, as shown at 32, the splines being formed in a hub 34 of the driving element 28. The details of the motor are not shown, as it is the usual type having a rotor provided with radial slots in which 30 slideable vanes reciprocate, the rotor being eccentric in relation to an outer casing of the motor, and suitable inlet and exhaust ports being provided in the usual manner. Motors of this type are in common use for operation by compressed air at pressures of seventy-five to one hundred and twenty-five pounds per square inch, and are particularly satisfactory for operation of an impact wrench of the kind disclosed, although other types, and even electric motors, may be 35 found satisfactory.

The driving element or carrier member 28 further has a parallel sided slot 44 therein which produces a top wall 40 and a bottom wall 42 in which impact members or hammer elements 46 are mounted with slight looseness. These hammer elements, in the present instance, are in the form of rollers.

Each roller 46 has, in its end, a socket 48 somewhat larger in diameter than a pin 50. Each of 50 the walls 40 and 42 of the driving element 28

has a pair of the pins 50 mounted therein as by a press fit. The pins 50 limit both the inward and the outward movements of the rollers 46 for an important purpose, which will hereinafter appear.

To serve as a means to prevent wobble of the lower end of the driving element or carrier member 28 in Fig. 4 it is provided with a perforation 52 in which a pilot pin 54 is mounted. The pilot pin 54 has a flange 56 surrounding it and a portion 58 received in a socket 60 of the anvil shaft 16.

Although having the hammer elements or impact members 46 comprising rollers whereby the wear is evenly distributed has its advantages, slideable but non-rotatable hammer elements or impact members may be provided as in Fig. 5. The parts in this figure corresponding to the previous figures bear the same reference numerals, with the addition of *a*. The hammer elements or impact members 46*a*, it will be noted, are not round, but of such shape that they slidably fit the slot 44*a* without possibility of their turning therein. The sockets 48*a* for the limiting pins 50 are illustrated in the form of slots rather than enlarged openings. The impacting operation is substantially the same, with the edges of the anvil elements or abutments 26*a* and the cooperating edges of the hammer elements or impact members 46*a* suitably shaped so as to provide a camming action. Either the hammer element or the anvil element may have the cam surface formed thereon, or both of them may, as in Fig. 5, the prime consideration being that upon stalling of the motor the build-up of air pressure behind the vanes therein will tend to rotate the driving element 28*a*, and through the camming action effect inward movement of the hammer elements so that they pass the anvil elements.

Practical operation

Assuming the parts in the position shown in Fig. 2, and rotation being in a clockwise direction, it will be obvious that rapid rotation of the driving element 28 will cause the rollers 46 to remain outward due to centrifugal force, and limited in their outward movement by the pins 50 being engaged by the inner edges of the socket 48. The anvil-like projections or abutments 26 have cam faces 27, two of which, it will be noted, are engaged by the rollers or hammer elements 46. This will cause a positive drive from the driving element 28 through the rollers 46 to the anvil member 16—22—26 for rotating the wrench head 12 and thereby the bolt or nut while it is driven "home" and until such time that its resistance to turning increases to such a point that the faces 27 will cam the rollers 46 inwardly against the action of centrifugal force. The inward camming action will force the rollers as to the position of Fig. 3, and in this position it will be noted that the rollers are limited against inward movement by the outer edges of the sockets 48 engaging the pins 50. This prevents them from striking each other, as would be caused by their momentum when thrown inwardly by the cam faces 27, and thus tipping of the roller surfaces is avoided. The pins 50, by limiting the outward movement of the rollers or hammer elements 46, make it unnecessary to provide an annular track carried by the anvil member for them to roll on, and has the further desirable effect of stopping the rotation of the rollers between impact blows on the anvil-like

projections or abutments 26. After the rollers pass the anvil elements in their rotation beyond the Fig. 3 position they are again thrown outwardly by centrifugal force, and the friction be-

5 tween the sockets of the rollers and the pins 50 stop them from rotating before they again strike the next succeeding anvil-like projections. Thus they do not have a tendency to roll up over the cam face 27, as would be the case if they were 10 rotating because of having traveled on an annular track, and a more positive impact blow is delivered due to the type of coaction thus had.

It will be noted that the essential features of 15 the invention are a driving element, a driven element and a driving connection between the two, which consists of hammer elements or impact members which are movable radially of the driving element. Accordingly, the hammer elements or impact members may normally re- 20 main outward by centrifugal force for causing simultaneous wrench rotation with motor rotation, and are cammed inwardly by the cam faces of the anvil element after stalling occurs due to the resistance to turning by the bolt or nut. 25 The centrifugal force of the hammer elements or impact members is suspended due to the stalling action, so that the cam faces 27 then effect their releasing action as the driving element 28 is urged to continue its rotation by the com- 30 pressed air behind the blades of the motor M. After that, centrifugal force and acceleration of the motor operate to bring the hammer elements into proper position for delivering suc- 35 cessive impact blows against the cam faces 27 as long as the tool continues to operate.

The arrangement disclosed is symmetrical about a plane through the axis of rotation so that rotation of the tool in either direction is possible with the desired impacting effect for

40 either tightening or loosening bolts and nuts. During the loosening operation, impact operation would occur until such time as the resistance to turning had decreased so that the rollers stay out by centrifugal force and positively rotate 45 the bolt or nut until the motor is stopped. Compared with devices in the prior art, the structure herein disclosed is substantially simple from the standpoint of having but few parts, and those parts simple in construction so as to be inexpensive for renewal, while, at the same time, all mechanical complications of operation are minimized.

The driving element or carrier member 28 is 50 comparatively easy to make because the slot 44 therein requires only a broaching operation for its formation. By then having the pins 50 limit the rollers 46 against inward movement, the rollers are kept out of contact with each other, as would be the case if they were not so limited. 60 This minimizes wear on the rollers and increases the life of the tool considerably.

Although I prefer to have the hammer elements or impact members 46 in the form of rollers, they 65 may assume other shapes, as suggested in Fig. 5. A change of this character, and many others, may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. An impact clutch of the character described 70 comprising relatively rotatable driving and anvil

members, the driving member having a slot therein, a pair of roller elements carried in said slot and movable by centrifugal force outwardly therein, means of coaction between said roller elements and said driving element for delivering a series of rotational hammer blows to said anvil member in the rotation of the driving element relative to the anvil member, said roller elements being retained in said slot of said driving element by means of recess and pin means at the opposite ends of said slot to limit their movement outwardly relative thereto.

2. An impact clutch comprising relatively rotatable anvil and driving elements, a pair of abutments on the anvil element, the driving element having a slot therethrough, rollers constituting hammer elements, said rollers being mounted in said slot and confined thereby to positions substantially parallel to the axis of rotation of said driving element, and coacting pins and sockets in said slot and said rollers to limit the inward and outward movement of the rollers, said rollers being movable in response to centrifugal force to their outer limits of movement for delivering a series of rotational blows to said abutments, said abutments effecting inward movement of said rollers after an impact blow has been delivered.

3. A reversely acting impact clutch comprising relatively rotatable anvil and driving elements, spaced striking surfaces on said anvil arranged in an orbital path about the driving element, said driving member having a cross-slot, hammer elements movable therein comprising rollers having movement radially of the driving element into and out of the path of the striking surfaces, said rollers delivering a series of rotational hammer blows to said striking surfaces in either direction of rotation of the driving element relative to the anvil, and means of coaction between said rollers and said driving element to limit the outward movement of the rollers to such path and the inward movement to positions out of contact with each other.

4. A reversely acting impact clutch comprising relatively rotatable anvil and driving elements, spaced striking surfaces on said anvil arranged in an orbital path about the driving element, said driving element having a cross-slot, roller-like hammer elements movable therein into and out of the path of the striking surfaces, said hammer elements delivering a series of rotational hammer blows to said striking surfaces in either direction of rotation of the driving element relative to the anvil element, and means of coaction between said rollers and said driving element to limit the outward movement of the rollers to such path.

5. A tool of the character described comprising a rotary driven element, a rotary driving element therefor, a hammer element carried by said driving element for inward and outward movement relative thereto, centrifugal force effecting such outward movement, means to limit the outward movement to a path where the hammer element will contact said anvil-like projection only, and means of cooperation between said projection and said hammer element to return the hammer element inwardly upon continued rotation of the driving element after the hammer element has struck said anvil-like projection with an impact blow.
- 15 6. A device for accumulating torsional force in an impact tool comprising a rotary driving element; an anvil coaxial with and spaced from said driving element; and a rotative connection between said driving element and said anvil comprising a carrier member disposed coaxially between said anvil and said driving element and connected with said driving element for rotation at the same rate as said driving element, an abutment projecting from said anvil outside only a part of the periphery of said driving element and formed with two lateral cam surfaces, a pair of impact members carried by said carrier member and movable only radially with respect thereto, and means provided on said impact members and said carrier member for confining said radial movement between outer points where said impact members will strike said cam surfaces on rotation of said carrier member and inner points where said impact members will clear the inside of said abutment, outward radial movement of said impact members being effected by centrifugal force and inward radial movement by resistance of the work against turning torque and consequent movement of said impact members over 40 one of said cam surfaces.
